AVIATION SPARK PLUG (RADIO SHIELDED)

Julius Devine, New York, N. Y.

Application October 5, 1942, Serial No. 460,763

16 Claims. (Cl. 123—169)

My invention relates to spark-plugs, and more particular to spark plugs of the shielded type, which are used in aviation motors.

The principal objects of my invention are to produce a gas-tight seal between the central electrode and the ceramic core-member; to relieve mechanical stresses on said core-member; and to provide a combination which will resist the injurious effects of high temperature and temperature changes.

Numerous additional objects of the invention will be disclosed in the annexed description and drawing, which illustrate preferred embodiments thereof.

Fig. 1 is a vertical central section of the improved core-portion of the spark plug.

Fig. 2 is a vertical central section of the complete device.

Fig. 3 is a view, similar to Fig. 1 of a modification.

The device comprises a recessed central electrode 1, which has a firing head 3. The outer longitudinal wall of the shank of said electrode 1 is slightly tapered, so that the inner end-part 4 of said longitudinal wall is of greater transverse diameter than the outer end-part 5 of said longitudinal wall.

A copper rod 2 is electrically bonded to the wall of the recess of said electrode 1, in order to conduct the heat to the firing head 3, so as to keep the plug at proper and normal operating temperature. The outer longitudinal end of the shank of said electrode has a thread 6.

The firing-head 3 is enlarged relative to the shank of said electrode 1, thus providing a shoulder, on which a mica washer 7 is located. Rearwardly of said mica washer 7, said shank of the electrode 1 is provided with helically wound mica insulation 8, the inner end of which abuts washer 7.

An outer mica washer 10 abuts the outer end of insulation 8. Said outer mica washer 10 abuts the inner end-wall of the ceramic core-member 9. A contact terminal cap 11 is screwed upon thread 6. Said terminal cap 11 maintains the assembly between core-member 9, electrode 1, washers 7 and 10 and insulation 8. The inner hollow end-portion of the shank of electrode 1 is peened over the inner end-wall of terminal cap 11, so that said tight assembly is reliably maintained.

In effect, the mica washers 7 and 10, are extensions of the mica insulation 8. The insulating members can be made wholly or partially of flexible insulating material other than mica, such as a solid alkyd resin.

A gas-tight seal is thus produced by the insulation, between the electrode 1 and the ceramic core-member 9. The bore of said core-member 9 is tapered to correspond to the taper of the outer longitudinal wall of the shank of the electrode 1, and the insulation 8 is also correspondingly tapered.

The device of Fig. 3 is substantially the same in principle, as the device of Fig. 1. In Fig. 3, 10 the outer longitudinal wall of the shank of the electrode 1, is tapered so that the transverse diameter of the inner end-portion 12, is less than the transverse diameter of the outer end-portion 13.

15 In Fig. 3, the mica insulation 14, which corresponds to the mica insulation 8, terminates about one inch from the outer end of the shank of the electrode 1. Outwardly of the insulation 14, there is a sleeve of moisture-absorbing cement 15, whose outer end abuts the outer mica washer 10.

20 Fig. 1 shows a thin metal shell 16, preferably made of copper, which has an inner frusto-conical end-portion, which abuts the corresponding 25 part of the outer wall of the ceramic core-member 9.

25 In Fig. 3, additional flexible mica insulation 17 is located in abutting relation between the metal shell 16 and the core-member 9.

30 The outer end-portion of said metallic shell 16 is crimped over a metal gasket 20, which is located on shoulder 19 of the core-member 9.

A metal ring 21 abuts the crimped end-portion 35 of shell 16.

As shown in Fig. 2, a metal shielding sleeve 22 has a threaded portion 23 which is screwed into the thread of the bore of metal shell 24. The inner end-wall of metal sleeve 22, abuts a metal washer 27, which abuts the metal ring 21. The 40 ring 21 is forced tightly into position. A hard ceramic sleeve 25 is located in metal sleeve 22. Said sleeves 25 and 22 are separated by a flexible insulator 26, which is preferably made of mica, so that it can be helically wound. The inner end 45 of insulation 26 abuts the metal washer 27.

Said insulator 26 minimizes or prevents the cracking of the hard inner ceramic sleeve 25 and it produces a tight seal between sleeves 25 and 22. Said flexible insulator 26 also relieves vibration.

The metal sleeve 22 is a shield, in order to prevent the transmission of electrical disturbances from the spark-plug, to an adjacent radio receiving set.

50 55 The combination of flexible mica insulation and of hard ceramic insulation, is of great value.

The fuels which are now used in internal combustion engines of the high-compression type, act injuriously upon mica. However, mica does not crack under heat, while ceramic insulation does crack. The ceramic insulation protects the mica insulation, and the mica insulation minimizes the cracking of the ceramic insulation. Even if the ceramic insulation does crack, the mica insulation will keep the plug functioning for a substantial period.

The thin metal housing 16, which is preferably made of copper is connected to the ceramic core 9, so as to produce a gas-tight joint. This thin metal housing compensates for irregularities in the ceramic core-member 9, thus producing a gas-tight joint with the metal shell 24.

Fig. 2 shows the gas chamber 29, the grounded electrode 30, and the firing-gap 31.

The additional flexible mica insulation 17, protects the core-member 9 from stresses which are produced when the metal ring 21 is forced into position. However, the use of such additional insulation 17 is optional.

The mica insulation used herein, is of the type known as "cigarette" mica. This is flexible and compressible.

As shown in Figs. 1 and 3, I provide a sub-assembly of the electrode and core-member by means of nut 11, which compresses the tapered mica insulation 8 between the correspondingly tapered proximate longitudinal walls of the electrode and the core-member. The crimped part of housing 16, with or without the insulation 17, provides a gas-tight fit between said crimped part and the respective shoulder of the core-member.

I have shown preferred embodiments of my invention, but it is clear that numerous changes and omissions and additions can be made without departing from its scope.

I claim:

1. For use in a spark-plug, the sub-combination of a rigid core-member made of ceramic insulating material, said core-member being hollow, an electrode located in said core-member, said electrode having a firing end which projects outwardly of said core-member, the proximate longitudinal walls of said electrode and of core-member being correspondingly tapered, compressible insulation means located wholly between and wholly abutting said proximate walls, assembly means holding said electrode and core-member in fixed relation and maintaining said insulation means under pressure and in contact with said proximate walls to produce a gas-tight seal between said proximate walls; said assembly means being fixed to one of said elements of said sub-combination, said proximate walls extending substantially to said firing-end.

2. For use in a spark-plug, the sub-combination of a rigid core-member which is made of insulating material, said core-member having a longitudinal through-and-through bore, an electrode located in said bore and extending longitudinally outwardly beyond each end of said bore, one end of said electrode having an enlarged head which is external to said core-member, said head having an end-wall which is proximate to and which is spaced from the respective end-wall of said core-member, said electrode and said bore having proximate walls which are correspondingly tapered, the end-portion of said electrode which is opposed to said enlarged head having a thread which is external to said core-member, a nut seated on said thread, said nut being external

to said core-member, said nut having an end-wall which is proximate to the respective end-wall of said core-member, compressible insulating means located between and abutting the aforesaid proximate walls, said nut maintaining said insulating means under compression to provide a gas-tight seal between each said pair of proximate walls.

3. For use in a spark-plug, the sub-combination of a hollow and rigid core-member made of insulating material, an electrode located in said core-member, at least one end of said electrode projecting from said core-member, said electrode being spaced wholly from said core-member, compressible spacing means made of insulating material and spacing said electrode from said core-member, assembly means connected to one of the elements of said sub-combination and holding said spacing means under pressure and holding said core-member and electrode in fixed relation.

4. In a spark plug comprising a shell a central electrode, a mica insulator encircling said electrode, a secondary insulator comprising of ceramic having an outer shoulder encircling said mica insulator, a copper housing having an annular bore encircling said ceramic insulator and crimped over the outer shoulder of the said ceramic insulator, a copper conductor through the center of said central electrode to conduct excessive heat from the firing electrode head to the cooler part of the plug and to conduct excessive heat from the gas chamber by the use of the copper housing encircling the ceramic insulator.

5. In a spark plug having a cylindrical nut engaging a shell, and tapered central electrode extending therewith, a mica sleeve, having an outer taper encircling said tapered electrode, a ceramic member having a shoulder on the outer surface encircling said insulator sleeve, copper housing having an inner annular surface encircling the said mica sleeve, the said copper housing having an annular outer surface to register with an annular seat in the shell to act as shock absorber to the ceramic and to relieve the mechanical stress on the ceramic when the latter is pressed in against the annular seat in the shell by the action of the threaded cylindrical nut.

6. In a spark plug comprising a mica insulator sleeve tapered inwardly to engage a tapered electrode, a ceramic member having an inner taper to engage the said mica sleeve outwardly and an outer taper having a shoulder at its upper end to engage a copper housing member, the largest part of said housing member is crimped over the shoulder of said ceramic to effect a gas-tight seal between the shoulder of said ceramic member and said crimped part of the copper housing.

7. In a spark plug an annular ceramic insulator having an electrode therein an annular copper housing member having an annular bore to register with said annular ceramic member and interposing means preferably mica between the inner surface of the said annular copper housing member and the outer surface of said annular ceramic member and so arranged as to have the upper part of said copper housing member crimped over a shoulder of the ceramic member to effect a gas-tight seal on top of the said ceramic shoulder.

8. In a spark plug comprising a tapered mica insulator inwardly tapered to engage a tapered

electrode, a ceramic member having an inner taper to engage the said mica insulator, said ceramic member having an outer shoulder to engage a copper housing extending above the ceramic shoulder and crimped over said ceramic shoulder of said ceramic member to effect a gas tight seal between the copper housing and said ceramic member over said ceramic shoulder.

9. In combination with a spark plug a tubular metallic shield threaded at its lower end to screw into an opening of a hollow metallic shell, a ceramic core member seated within said metallic shell, and a tubular ceramic member seated within said metallic shield, compressible insulation means within said ceramic core member, together with compressible insulation means sleeved longitudinally about said tubular ceramic member and being in intimate contact there-

with and which means together serve to support and protect said ceramic members from cracking under intense heat and sudden atmospheric change.

- 5 10. In combination with a spark plug, a tubular metallic shield threaded at its lower end to screw into an opening of a hollow metallic shell, a ceramic core member seated within said metallic shell and a tubular ceramic member within
- 10 15 said metallic shield, compressible insulation means secured longitudinally within said ceramic core member and compressible insulation means secured about said tubular ceramic insulator outwardly to support, seal, and protect the said ceramic members from metallic stress, intense heat, and atmospheric change.

JULIUS DEVINE.
